UNITED STATES PATENT OFFICE.

JAMES A. COCHRAN, OF PITTSBURG, KANSAS.

VALVE.

1,090,279.

Specification of Letters Patent. Patented Mar. 17, 1914.

Application filed February 21, 1912. Serial No. 678,988.

To all whom it may concern:

Be it known that I, JAMES A. COCHRAN, a citizen of the United States, residing at Pittsburg, in the county of Crawford and State of Kansas, have invented new and useful Improvements in Valves, of which the following is a specification.

An object of the invention is to provide a valve, particularly adaptable for use on locomotive tanks to control the supply of water to the boiler of the locomotive and prevent foreign substances entering the boiler of the locomotive with the water.

Among other features the invention embodies a strainer casing secured within the locomotive tank and having mounted therein a valve member to which is pivotally connected a rod having an end thereof connected to an operating lever mounted on the locomotive tank and operable to actuate the said valve member to open or close the pipe for conveying the water from the locomotive tank to the boiler of the locomotive.

In the further disclosure of the invention, reference is to be had to the accompanying drawings constituting a part of this specification, in which similar characters of reference denote corresponding parts in all the views, and in which—

30 Figure 1 is a fragmentary sectional view of a locomotive tank showing my device in side elevation thereon. Fig. 2 is an enlarged vertical sectional view taken through the casing, the valve, however, being shown in full lines and in open position. Fig. 3 is a similar vertical sectional view showing the valve in closed position.

Referring more particularly to the views, I provide a locomotive tank 10 having connected thereto a pipe 11, a suitable valve seat 12 being formed on the floor of the tank 10, adjacent the point of connection of the pipe 11 with the tank 10. Secured to the floor of the tank 10, to encircle the valve seat 12 is a strainer casing 13 having a series of perforations 14 and mounted to slide vertically within the casing 13 is a valve 15, comprising a valve body 16 having the lower end thereof beveled for engagement with the valve seat 12, the mentioned valve body 16 being provided with a reduced portion 17 adapted to receive a ring 18, the upper end of the valve body 16 terminating in a cross head 19 to which is pivotally connected the lower end of a rod 20, having the upper end thereof connected to an operat-

ing lever 21, mounted on the outer side of the tank 10. For the purpose of limiting the vertical movement of the valve 15 in the strainer casing 13, a circular flange member 22 is threadedly connected with the upper end of the strainer casing 13 and is provided with a depending circular flange 23, against which the valve 15 is adapted to abut so that the flange 23 will limit the upward movement of the valve, the upper end of the casing 13 being received between the depending flange 23 and the body or threaded portion of the flange member 22.

Assuming that the valve is in lowermost position with the beveled portion of the valve body engaging the valve seat 12, when it is desired to permit the flow of water through the pipe 11, a downward pressure is exerted on the handle of the operating lever 21, thus moving the valve 15 vertically within the casing 13 to disengage the lower beveled portion of the valve from the valve seat. As the water passes through the perforations 14 of the strainer casing 13, any foreign substances contained in the water will be prevented from passing into the pipe 11 by the strainer casing, the perforations therein being sufficiently small to prevent various particles of coal from entering the pipe 11, it being well known that when foreign substances pass into the boiler of the locomotive they tend to form a scale on the inner side of the boiler casing. As mentioned heretofore, the flange member 22 will limit the upward movement of the valve 15 and by providing the ring 18 to extend a distance beyond the periphery of the valve body 16, the frictional engagement of the valve 15 with the inner side of the casing 13 will be greatly reduced and the valve can be conveniently and easily operated by actuating the lever 21.

I claim:—

In a valve, the combination with a perforated cylindrical strainer casing, of a valve seat formed at the lower end of the strainer casing and constituting a beveled wall of an entrance to the strainer casing, a valve mounted to slide vertically in the strainer casing, the said valve comprising a valve body having the lower portion thereof beveled for engagement with the beveled valve seat of the strainer casing, the medial portion of said valve body being cylindrical, and provided with a reduced portion encircled by a ring, the upper end of the valve

body terminating in a cross head, with the said medial portion of the valve body forming a circular guide for guiding the valve body in its movement in the casing, a rod 5 pivotally connected to the said cross head, an operating lever connected to the said rod for operating the valve body in the casing, and a circular flange member secured to the upper end of the casing and having portions projecting inwardly from the inner wall thereof to be engaged by the valve body 10

and limit the upward movement thereof, the upper end of the said casing being received in a circular groove formed in the said flange member.

15

In testimony whereof I affix my signature in presence of two witnesses.

JAMES A. COCHRAN.
